US0D1037491S

(12) **United States Design Patent** (10) Patent No.: **US D1,037,491 S**
(45) Date of Patent: ** Jul. 30, 2024

(54) **WALL BLOCK**(71) Applicant: **PAVESTONE, LLC**, Atlanta, GA (US)(72) Inventor: **William H. Karau**, Southlake, TX (US)(73) Assignee: **PAVESTONE, LLC**, Atlanta, GA (US)(***) Term: **15 Years**(21) Appl. No.: **29/819,307**(22) Filed: **Dec. 14, 2021**(51) LOC (14) Cl. **25-01**

(52) U.S. Cl.

USPC ..... **D25/113**(58) **Field of Classification Search**

CLAIM

The ornamental design for a wall block, as shown and described.

DESCRIPTION

FIG. 1 shows a front perspective view of a wall block according to a first embodiment of the present disclosure; FIG. 2 shows a front elevation view of the wall block illustrated in FIG. 1; FIG. 3 shows a rear elevation view of the wall block illustrated in FIG. 1; FIG. 4 shows a right side view of the wall block illustrated in FIG. 1; FIG. 5 shows a left side view of the wall block illustrated in FIG. 1; FIG. 6 shows a top view of the wall block illustrated in FIG. 1; FIG. 7 shows a bottom view of the wall block illustrated in FIG. 1; FIG. 8 shows a rear perspective view of the wall block illustrated in FIG. 1; FIG. 9 shows a front perspective view of a wall block according to a second embodiment of the present disclosure; FIG. 10 shows a front elevation view of the wall block illustrated in FIG. 9; FIG. 11 shows a rear elevation view of the wall block illustrated in FIG. 9; FIG. 12 shows a right side view of the wall block illustrated in FIG. 9; FIG. 13 shows a left side view of the wall block illustrated in FIG. 9;

FIG. 14 shows a top view of the wall block illustrated in FIG. 9;

FIG. 15 shows a bottom view of the wall block illustrated in FIG. 9;

FIG. 16 shows an environmental view of the wall block illustrated in FIG. 9;

FIG. 17 shows a front perspective view of a wall block according to a third embodiment of the present disclosure; FIG. 18 shows a front elevation view of the wall block illustrated in FIG. 17;

FIG. 19 shows a rear elevation view of the wall block illustrated in FIG. 17;

FIG. 20 shows a right side view of the wall block illustrated in FIG. 17;

FIG. 21 shows a left side view of the wall block illustrated in FIG. 17;

FIG. 22 shows a top view of the wall block illustrated in FIG. 17;

FIG. 23 shows a bottom view of the wall block illustrated in FIG. 17;

FIG. 24 shows a rear perspective view of the wall block illustrated in FIG. 17;

FIG. 25 shows a front perspective view of a wall block according to a fourth embodiment of the present disclosure; FIG. 26 shows a front elevation view of the wall block illustrated in FIG. 25;

FIG. 27 shows a rear elevation view of the wall block illustrated in FIG. 25;

FIG. 28 shows a right side view of the wall block illustrated in FIG. 25;

FIG. 29 shows a left side view of the wall block illustrated in FIG. 25;

FIG. 30 shows a top view of the wall block illustrated in FIG. 25;

FIG. 31 shows a bottom view of the wall block illustrated in FIG. 25; and,

FIG. 32 shows a rear perspective view of the wall block illustrated in FIG. 25.

The dashed broken lines illustrate portions of the wall block and form no part of the claimed design. The dot-dash broken lines illustrate boundaries of the claimed design and form no part thereof.
